United States Patent Office

Des. 197,261
Patented Dec. 31, 1963

197,261

BOAT

Gerald W. Hoos, 1803 Monroe St., Evanston, Ill.

Filed Sept. 24, 1962, Ser. No. 71,813

Term of patent 14 years

(Cl. D71—1)

FIG. 1

FIG. 2

FIG. 3

FIG. 4

FIG. 5

FIG. 6

The side not shown is a mirror image of the side shown.

I claim:
The ornamental design for a boat, as shown and described.
